CLAIM

The ornamental design for a illuminated clamp handle for an umbrella, as shown and described.

DESCRIPTION

FIG. 1 is a perspective view of an illuminated clamp handle for an umbrella showing my new design;

FIG. 2 is a left side elevational view of the clamp handle of FIG. 1;

FIG. 3 is a right side elevational view of the clamp handle of FIG. 1;

FIG. 4 is a front elevational view of the clamp handle of FIG. 1;

FIG. 5 is a rear elevational view of the clamp handle of FIG. 1;

FIG. 6 is a top plan view of the clamp handle of FIG. 1; and,

FIG. 7 is a bottom plan view of the clamp handle of FIG. 1.

The broken line showing of an umbrella in FIG. 1 is for illustrative purposes only and forms no part of the claimed design.
